UNITED STATES PATENT OFFICE.

FRANK P. DEISSLER AND FRANK W. DICKINSON, OF GREENVILLE, PENNSYLVANIA.

CAR-COUPING.

1,198,012.

Specification of Letters Patent. Patented Sept. 12, 1916.

Application filed November 30, 1915. Serial No. 64,222.

To all whom it may concern:

Be it known that we, FRANK P. DEISSLER and FRANK W. DICKINSON, citizens of the United States, residing at Greenville, in the county of Mercer and State of Pennsylvania, have invented certain new and useful Improvements in Car-Couplings, of which the following is a specification.

This invention relates to all types of car couplers having a locking device or pin adapted to be raised to uncouple the coupler heads by means of a lever and rock shaft pivoted or mounted upon the car sill and extending to the side of the car, and has for its object to provide means, in a manner as hereinafter set forth, for connecting the uncoupling lever and the locking pin, with means having provision in connection with an element carried by the end of the uncoupling lever for slidably connecting said end of the uncoupling lever to said means and the latter further set up so as to provide a guide for the shifting movement of the free end of the uncoupling lever.

A further object of the invention is to provide, in a manner as hereinafter set forth, a rigid element between the end of the uncoupling lever and the locking pin, at the same time providing a sliding connection between the uncoupling element and said rigid element, and by such an arrangement overcoming the employment of a chain or link connection between the inner end of the uncoupling lever and the locking pin.

Further objects of the invention are to provide, in a manner as hereinafter set forth, a sliding connection between a locking pin lifting element and the inner end of an uncoupling lever, said lifting element being of one piece, and said connection being simple in its construction and arrangement, providing a guide for the inner end of the uncoupling lever, strong, durable, providing a housing for the inner end of the uncoupling lever to prevent said end from becoming damaged, efficient in its use, readily set up with respect to the inner end of the uncoupling lever and a locking pin, and comparatively inexpensive.

With the foregoing and other objects in view the invention consists of the novel construction, combination and arrangement of parts, as hereinafter more specifically described and illustrated in the accompanying drawing, wherein is shown an embodiment of the invention, but it is to be understood

that changes, variations and modifications can be resorted to which come within the scope of the claims hereunto appended.

In the drawings wherein like reference characters denote corresponding parts throughout the several views:—Figure 1 is a side elevation of a coupler head and uncoupling lever and showing the adaptation with a lever and a locking pin of a lifting element in accordance with this invention. Fig. 2 is a front elevation illustrating the elements referred to in connection with Fig. 1. Fig. 3 is a perspective view of a locking pin element.

Referring to the drawings in detail 1 denotes a coupler head, provided with a locking pin 2, having an apertured extension 3.

4 denotes the side of a car, 5 the car sill, 6 an uncoupling lever journaled in a support 7; the inner end of the uncoupling lever is provided with a head 7' formed with an opening.

Associated with the inner end of the uncoupling lever 6 and the apertured extension 3 of the locking pin 2 is a lifting element consisting of a hollow substantially oval-shaped body portion 8 having each of its sides provided with a vertically disposed elongated oval-shaped slot 9. The slots 9 are arranged in parallelism. Formed integral with the lower end of the body portion 8 is a depending tapering tongue 10, which terminates in a hook 11; the latter is adapted to be connected to the apertured extension 3 and the opening in such extension is of such diameter with respect to the diameter of the hook to set up a loose connection between said hook 11 and the apertured extension 3.

The head 7' at the inner end of the uncoupling lever extends into the body portion 8 and is slidably connected therewith by a pin 12 having an enlarged head 13 which slides against the outer face of one of the sides of the body portion 8. That end of the pin 12 which is not provided with a head has mounted thereon a disk 14 which slides against the outer face of the other side of the body portion 8 and is maintained in position upon the pin 12 by a cotter-pin 15. The pin 12 extends through the apertured head 7 of the uncoupling lever.

By setting up the locking pin lifting element in a manner as stated it overcomes the employment of a chain connection between the uncoupling lever and said locking pin

and furthermore as the head of the uncoupling lever extends into the body portion 8, the latter provides a housing for such head and reduces to a minimum the possibility of damage. The pin or slot connection between the head and body portion 8 allows for free movement of the inner end of the coupler lever and furthermore the body portion 8 constitutes a guide for the vertical movement of said head 7'. The upper and lower ends of the slots 9 limit the vertical movement of the head.

As the lifting element is formed in one piece breakage thereof is reduced to a minimum and overcomes the objection present when a chain is employed as the latter will sometimes buckle and the links are allowed to become broken or bent and retard the necessary movement of the uncoupling lever.

20. What we claim is:—

1. In a car coupler the combination with the inner end of an uncoupling element, of a housing inclosing said inner end, said housing provided with slots, means extending through said slots and said end for slidably connecting said end to said housing,

and a hook integral with the bottom of the housing and adapted to be connected to the locking pin of a coupler.

2. A locking pin lifting element adapted 30 to have an uncoupling lever connected therewith and consisting of a housing having the side walls thereof slotted, and a hook integral with the lower end of a housing.

3. In a car coupler the combination with the inner end of an uncoupling element, of a housing inclosing the inner end and having its sides provided with slots, a pin extending through said slots and inner end 40 for slidably connecting said inner end to the housing, and a hook projecting from the bottom of the housing and adapted to be connected to the locking pin of a coupler.

In testimony whereof we affix our signatures in the presence of two witnesses.

FRANK P. DEISSLER.
FRANK W. DICKINSON.
